UNITED STATES PATENT OFFICE.

SAMUEL TRETHEWEY, OF PITTSBURG, PENNSYLVANIA.

SLIDE-VALVE.

SPECIFICATION forming part of Letters Patent No. 240,286, dated April 19, 1881.

Application filed January 28, 1881. (Model.)

To all whom it may concern:

Be it known that I, SAMUEL TRETHEWEY, of Pittsburgh, county of Allegheny, State of Pennsylvania, have invented or discovered a new and useful Improvement in Steam-Engine Slide-Valves; and I do hereby declare the following to be a full, clear, concise, and exact description thereof, reference being had to the accompanying drawings, making a part of this specification, in which—like letters indicating like parts—

Figure 1 is a central sectional view of a part of a steam-engine cylinder, a steam-chest, with its ports and passages, and a tubular slide-valve, the same being illustrative of my invention. Fig. 2 is a transverse sectional view of the steam chest and valve, taken in the plane of the line xx , Fig. 1. Fig. 3 is an enlarged view, partly in section and partly in elevation, of my improved valve. Fig. 4 is a transverse sectional view of the valve, taken in the line yy , Fig. 3; and Fig. 5 is a sectional view of a detached portion of the valve, taken in the line zz , Fig. 4.

My invention relates to certain improvements in steam-engine slide-valves; and, in general terms, it consists in making such valve of tubular form, having a shell divided longitudinally, so as to expand under internal pressure, with steam-ports in the shell arranged to register with passages in the steam-chest leading to the supply-pipe, and also with passages to both ends of the cylinder, whereby the interior of the valve constitutes a part of the steam-supply passage, the ends of such shell being closed and its length divided, as herein-after described, and, further, in combining such valve with a chamber adapted in form to hold the parts of the valve together while in use.

In the drawings, $A A'$ represent parts of a steam-engine cylinder and piston. B is the steam-chest; $a a'$, steam-passages leading from the chest to either end of the cylinder. $b b'$ are exhaust-ports. C is the steam-supply pipe, leading, by branch passages C' , to annular passages or chambers cc' , which surround and open into the valve-chamber H . These parts, except as hereinafter described, may be of any desired form adapted to co-operate with my improved valve, which is arranged, constructed, and operated as follows:

The body of the valve is formed of a tubular shell, E , which is divided longitudinally into two parts, as at e , Fig. 3. The two ends of this divided shell are closed by heads i and i' , which are connected, by stems or rods $F F'$, with a central distance piece or disks, ff' , which latter serves as a diaphragm to divide the interior of the shell transversely, and also affords means for securing the valve to the stem, as presently described. This distance-piece ff' is made of two separate disks, which are cast or rigidly secured to the separate parts of the divided shell, one to each. By overlapping, as shown, such disks effect the desired separation between the parts of the interior, and also allow adjustment or motion of the shell, as required.

The head i , which closes the upper end of the shell E , is secured to one disk, f , of the distance-piece by a rod, F , the head being secured on one end of the rod in any convenient way, as by nut m and collar m' , while the inner end of the rod is screwed or otherwise fastened into the disk. The other head, i' , is secured on the stem F' , either by nut and collar, or, as shown, by means of a conical enlargement, n , on the stem fitting a correspondingly-shaped hole through the head, the taper of such enlargement holding the head in one direction, and a key, n' , holding it from moving in the opposite direction. The inner end of stem F' is screwed into the disk f' of the central distance-piece, and thus makes attachment with the valve. The heads i and i' are packed or made expansible, so as to fill the ends of the shell by means of elastic or spring bands r , which are seated in grooves r' , sunk in the peripheries of the heads. These bands are cut or open, and the joint thus made is broken by lapping projections r^2 . (See Fig. 3, at bottom.) When in place the bands are under compression, and by their tendency to expand they not only close the space between the peripheries of the heads and the shell, but also tend to press the parts of the shell against the walls of the valve-chamber H , and thereby prevent leakage either through or around the ends of the valve.

In order to close passage through the openings e at the ends, and also to prevent one part of the shell from slipping longitudinally

on the other part, gluts s are inserted in openings s' , made in the shell, across the line e , at either end. These gluts conform in outline to the surfaces of the shell. They are by preference made to fit tightly in one side or part of the openings s' , and a dovetail fitting may be employed for this purpose, if desired; also, the side edges of the gluts may be fitted to the edges of the openings by Δ -shaped grooves and projections, as at s'' , Fig. 5. But in any case it is desirable to provide for some motion of the glut in one part of the shell or opening, so as to allow expansion. This may be done by the means shown and still the joint be made practically steam-tight. The gluts being of the same thickness as the shell and arranged in the planes of the heads $i i'$, as shown, the bands r will press them against the inclosing-wall of the valve-chamber along with the shell.

The valve-chamber H is bored round and true, and the outer surface of the shell is similarly fitted, so as to fit closely within the chamber and bear against its walls through its length and circumference, except where openings are made in either for steam-passages. While thus inclosed the parts of the valve cannot become separated, and yet they are free to such extent as to permit the shell to expand under internal pressure.

Near the outer ends of the shell are made ports h and h' in any desired number, which in the travel of the valve register alternately with the passages $a a'$. Also, near the center of the shell, on either side of the distance-piece ff' , are made ports k and k' in any desired number, which are so arranged with relation to the ports $h h'$ and passages $c c'$ that when the ports at either end register with the passages a or a' , as the case may be, the ports k or k' on the same side shall also register with the annular supply-passages c or c' . As shown in Fig. 1, the ports h' register with a' , and the ports k' on the same side register with passage c' . On the other side of the distance-piece the ports h and k are closed by the chamber-wall, and are out of communication with both a and c . In such construction steam is admitted to the cylinder from the steam-pipe through the valve, which thus forms a part of the steam-passage.

The exhaust-ports b and b' lead from the valve-chamber outside of or beyond the passages $a a'$, so that the end of the valve closes the exhaust as soon as it enters that part of the chamber, as shown at the lower end of Fig. 1, and in such position the bands r serve to press or expand the end of the valve-shell against the inclosing-wall, and thereby pack the same or prevent leaking, as above described.

Any desired lap may be provided by properly arranging the position and width of the ports and passages.

It will be observed that as the valve moves to open the exhaust the ports h or h' are closed before the exhaust is opened, and as a result

both parts or ends of the valve are at all times, when in operation, filled with steam at nearly equal pressure, giving practically equal pressure of steam on the shell through its length, and also the distance-piece ff' is balanced by pressure on opposite sides, and consequently no great accuracy is required in fitting such parts. This steam-pressure within the valve-shell is employed to secure one of the principal objects of my invention—that is, to press or expand somewhat the valve-shell against the walls of the chamber, and thereby pack the valve, and also enlarge it as the valve and chamber wear by use, so as to fill or fit properly. To this end the shell is made of proper thickness and material to yield under the usual pressure of steam employed. Also, the longitudinal division of the shell is made with special reference to this end, and renders my improved valve self-compensating for wear to a greater extent than is true of other valves of this class of which I have knowledge.

Instead of dividing the shell into two separate parts, a single slit, e , may be made therein from end to end, so that the shell may open under pressure, though, for convenience of construction, I prefer to make the shell in separate parts, as shown and described. Owing to the great extent of surface-bearing between the shell and its inclosing-wall, the pressure of the shell thereon is not an impediment to the proper working of the valve, but, on the contrary, prevents leakage between such surfaces by an operation equivalent to automatic packing.

I have designed my improved valve more especially for use in steam-hammers, and have found by use that it is well adapted therefor, and is free from several objections which have attended the use of piston and other valves, such as bounding, wearing, and leaking. My improvement is well adapted for other use in steam-engines, however, and I do not wish to limit its application to hammers and similar uses.

The valve-stem F' may be packed, as at D , in any suitable way, and suitable or well-known means are to be employed for operating the valve and for fitting the parts of the engine.

I claim herein as my invention—

1. An expansible slide-valve having a tubular shell divided longitudinally, with expanding heads for closing the ends of the shell, a two-part distance-piece, ff' , and inlet and outlet ports in the shell on both sides of the distance-piece, substantially as described.

2. A tubular slide-valve having, in combination, a longitudinally-divided shell, heads $i i'$, elastic bands r , gluts s , arranged in the planes of the bands across the line of division between the parts of the shell, distance-piece ff' , and inlet and outlet ports in the shell on both sides of the distance-piece, substantially as set forth.

3. A tubular expansible slide-valve having a cylindrical shell, E , divided longitudinally into separate parts, with gluts s , expansible

heads for closing the ends of such shell, and two-part distance-piece arranged centrally across the interior of the shell, with inlet and outlet ports in the shell on both sides of the 5 distance-piece, in combination with steam-chest B, having valve-chamber H therein, adapted in form and size to hold the parts of the valve together, and having steam-passages $a a' c c'$,

arranged to register with the ports of the valve, substantially as set forth.

In testimony whereof I have hereunto set my hand.

SAMUEL TRETHEWEY.
